UNITED STATES PATENT OFFICE.

FRED HENRY GILE, OF CLIFTONDALE, MASSACHUSETTS, ASSIGNOR, BY MESNE ASSIGNMENTS, TO GEORGE K. WOODWORTH, TRUSTEE, OF BROOKLINE, MASSACHUSETTS.

INTERNAL-COMBUSTION ENGINE.

1,335,322.

Specification of Letters Patent. Patented Mar. 30, 1920.

Original application filed April 5, 1915, Serial No. 19,265. Divided and this application filed March 23, 1916.
Serial No. 86,271.

To all whom it may concern:

Be it known that I, FRED HENRY GILE, a citizen of the United States, and a resident of Cliftondale, in the county of Essex and State of Massachusetts, have invented a new and useful Improvement in Internal-Combustion Engines, of which the following is a specification.

My invention relates to internal combustion engines and more especially to lubricators for the rubbing surfaces between the cylinder and piston head.

An illustrative embodiment of my invention is shown in the accompanying drawings in which—

Figure 1 is a vertical longitudinal section, certain parts being shown in elevation, of an internal combustion engine having a piston-rod constructed to coöperate with my improved lubricator. Fig. 2 is a side view of said engine with my lubricator applied thereto. Fig. 3 is a longitudinal section on an enlarged scale of said lubricator. Fig. 4 is a plan view of the cylinder shown in Fig. 1 with the cylinder-head removed and illustrating the oil ducts in the piston head.

In the particular drawings selected for more fully disclosing my invention, 1 represents a frame having a horizontal crank-shaft 2 suitably journaled therein and supporting the cylinder 3, the ends of which in the present instance are provided with a number of parallel fuel passages or flutes 4, 4' arranged lengthwise in its bore and communicating with and extending into the combustion chambers A A' respectively.

While I do not limit myself to the number of flutes that may be employed I have found that from sixteen to twenty give good results. No hard and fast rule can be given as to the number of the flutes that will give the best results under all conditions of operation. They are not mere passageways or channels from the space between the pistons to the combustion chamber; but on the contrary they serve the additional function hereinafter more fully set forth of effecting a perfect or substantially perfect mixing of the charge of fuel and air. Their number depends in a way upon the volume of the cylinder and their total cross sectional area depends upon the cross sectional area of the intake port. There must be a relatively large number of flutes so as thor-

oughly to subdivide the charge and effect the complete mixing of the same. The total cross sectional area of the flutes must be such, due regard being had to the cubical contents of the cylinder and the cross sectional area of the intake port, that they will impose sufficient restraint to the passage of the gas therethrough as to enable the latter to acquire a relatively high velocity during such passage. Arranged to reciprocate within the cylinder is a hollow piston or sub-piston consisting of two heads 5, 5' rigidly connected by the rods 6 herein shown as three in number, and the lower head is connected to or integral with the hollow piston-rod or sleeve 7, which in turn is secured to the cross-head 8 guided in the ways 9 on the engine frame. Arranged to reciprocate within the cylinder and within the hollow piston is a plunger or power-piston 10 connected to or integral with the piston-rod 11 which passes axially through the lower head of the sub-piston and the hollow piston-rod 7, and is secured at its lower end to the cross-head 12 guided by the ways 9. The pitman 13 connects the cross-head 12 with the crank 14 to transmit the power developed in the cylinder to the main crank-shaft.

Pivottally connected to the studs 15 arranged on opposite sides of the cross-head 8 are the connecting rods 16, one on either side of the pitman 13, and said connecting rods engage the arms 17 which are rigidly connected with the rock-shaft 18 journaled in the engine frame, said arms being arranged on opposite sides of said pitman. Integral with or rigidly connected to one of the arms 17 is a shorter arm 17' to which is pivoted a connecting rod 19 engaging the outer end of the bell-crank 20 pivotally connected to the frame at 21.

The two arms of the bell-crank are bifurcated and the rolls 22, 23 are journaled between the forks of the upper and lower arms respectively. The cams 24, 25, rotating with the main shaft engage the rolls 22, 23, respectively. Either one of the two cams is cut to communicate the proper motion to the arm of the bell-crank with which it coöperates, and then the other cam is so cut that the two rolls are always held positively in contact with their respective cams, thereby eliminating the necessity for the

usual spring arrangement employed to maintain firm contact between a cam and its follower.

The cylinder is provided with exhaust passages 26, 26' controlled by the inwardly-opening valves 27, 27' normally held on their respective seats by the springs 28, 28' which surround the valve stems and have their ends bearing against the outer walls of the exhaust passages and the collars 29, 29' on the valve stems. Coöperating with the ports in the cylinder-head extensions 30 are the outwardly-opening automatic check-valves 31, 31', each held on its seat by the relatively light springs 32, 32' interposed between the collars 29, 29' and the ends of their hollow stems 33, 33', which, as shown, are guided in the bosses 34, 34'.

It will be understood of course that the exhaust valves may be operated by any suitable mechanism and in the present case I have illustrated a simple form of valve gearing comprising continuously rotating cams operatively connected with the power shaft. The tappet 35 secured to the rock-shaft 36 strikes the lower end of the stem of the valve 27, thereby forcing the same upwardly from its seat at the proper times, and said rock-shaft 36 is suitably connected through the rock-lever 37 and shifting-rod 38 to one of said continuously rotating cams which coöperates with a collar on the lower end of said shifting-rod, said cam not appearing in Fig. 1 because it is secured to the cross-shaft 41 directly behind the cam 40. The valve 27' is raised from its seat at the proper times by said cam 40, which coöperates with the collar 40' on the lower end of a short shifting rod which engages the lower end of its valve stem. It will be understood of course that the valves are closed by their respective springs 28, 28' as soon as the cams pass their coöperating elements.

The cross-shaft 41 to which said cams are secured may be connected with the power shaft by any suitable means, for example, by the shaft 60, having bearings at 61 and the gears 62, 63.

The fuel inlet 42 located substantially midway between the two ends of the cylinder is connected by a pipe 42' to any suitable source of fuel.

For lubricating the cylinder I prefer the pump shown in Fig. 3, which communicates with the longitudinal duct 43 passing through the piston-rod 11 and intersecting the transverse ducts 44 in the power-piston, said transverse ducts being shown herein as three in number and intersecting the bores in the power-piston through which the rods 6 pass. The pump is supported by the bracket 45 which is connected to the cross-head 12 and comprises a barrel 46 carrying a plunger 47, the head 48 of which normally held in retracted position by the surrounding spiral

spring 49 is arranged to strike the adjustable stop 50 during the reciprocation of said cross-head. The tube 51 connects the bottom of a chamber 52 with the lower portion of the pump barrel and a tube 53 communicates between said chamber and the duct 43 in the piston-rod. A tube 54 connects the bottom of the barrel with the bottom of the lower member of a pair of telescoping tubes 55, 56, the upper member of which is connected by the pipe 57 to a source of lubricating oil. Valves of any suitable type, herein shown as gravity-actuated ball-valves 58, 59, normally close the lower ends of the pump barrel 53 and the chamber 52 respectively.

It will be understood of course that the foregoing detailed description comprises various elements which in the precise form shown in the drawings and described herein are not essential to my invention and that these parts may be considered simply as typical of the necessary elements of an internal combustion engine.

By means of flutes or fuel passages 4, 4' I am enabled to secure an intimate and practically perfect mixture of the fuel thereby insuring complete combustion of said charge on ignition.

As the power-piston approaches the head of the hollow piston the charge which is contained in the space between these two elements is compressed and forced by such compression around the advancing head of the hollow piston through the flutes or fuel passages and is shot with great force against a solid body, which in the present instance is the cylinder-head, in a number of relatively small streams, the number of said streams being sufficiently large to effect such a thorough, intimate and complete mixing of the charge that substantially complete combustion of the same in the cylinder will result on ignition.

An explosion of the compressed charge in either combustion chamber acts directly on one of the heads of the sub-piston and by the latter is communicated to the power-piston with which such head is then in contact as shown in Fig. 1. It is absolutely necessary that the two pistons shall travel at the same rate of speed without the slightest relative movement until the hollow piston, or sub-piston, shall have covered the inner ends of the adjacent set of flutes and it is essential that the subsequent relative movement between the pistons be created positively and that the sub-piston be controlled positively as distinguished from the construction shown in my prior Letters Patent No. 735,964, issued August 11, 1903, which has a flying piston somewhat similar in form to the hollow piston of the present invention but not controlled positively nor arranged for positive relative movement

with respect to the power-piston; and it is highly desirable that they shall remain in contact until the end of the power-stroke of the sub-piston or during a substantial portion of such power-stroke.

It will be obvious that the means governing the movement of the hollow piston must be carefully designed to prevent any relative movement with respect to the power-piston until the hollow piston shall nearly have reached the end of its stroke, and particularly until the trailing head of the hollow piston shall have covered the inner ends of the adjacent set of flutes. The reason for this will be obvious from an inspection of Fig. 1 in which the parts are shown in the position occupied immediately prior to ignition in the combustion chamber A. Should the power-piston begin to move away from the upper head 5 of the sub-piston before the latter covers the inner ends of the flutes 4, a portion of the effect of the explosion will be exerted against the lower face of said head 5 in opposition to the force exerted on the upper face thereof.

The hollow piston is governed or controlled throughout the entire cycle by the cams 24, 25, which as above described, operate the bell-crank 20 and the latter is connected through the motion-reducing connection 17, 17' with the cross-head 8. The cams are so designed and are so related to the crank 14 that both pistons travel in the same direction, for example, downwardly having reference to Fig. 1, at the same initial rate of speed and without relative motion until the lower head 5' of the hollow piston nearly reaches the bottom of the cylinder, then, while the power piston is continuing its descent, the sub-piston is slightly recalled until the upper face of its lower head 5' is a little below the inner ends of the flutes 4', in which position the cam surfaces are concentric with the power-shaft and consequently the sub-piston is held stationary until the power-piston reaches the end of its stroke.

While it will be understood that the several moving parts may be variously adjusted and timed, I prefer such adjustment and timing as will produce the following cycle.

When both pistons are at the upper end of their strokes, the upper head 5 of the sub-piston being in contact with the power piston, as shown in Fig. 1, and the charge compressed in the combustion chamber A, the valve 27 being closed and the valve 27' open or about to open, the charge is fired and the resulting explosion causes both pistons to descend at the same rate of speed and without any relative movement until the sub-piston nearly reaches the bottom of the cylinder driving the burnt gases of the preceding explosion out of the combustion chamber A' and through the exhaust passage 26'.

The sub-piston is now recalled until the upper face of its lower head 5' is slightly below the inner ends of the flutes 4' and the lower face of its upper head 5 slightly above the fuel inlet 42, in which position it remains stationary until driven upwardly by the next explosion in the combustion chamber A'.

The power-piston 10 continues its descent and, after uncovering the fuel-inlet 42, creates a partial vacuum within the trailing end of the hollow or sub-piston and draws a charge of fuel through said inlet into the space between its upper face and the lower face of the upper head 5 of said hollow piston. At the same time the plunger or power-piston 10 compresses the charge in the advancing end of the hollow piston, *i. e.*, in the space between its lower face and the upper face of the lower head 5' of said hollow piston, a charge of fuel having been drawn into said space on the preceding up-stroke of the pistons, and a portion of this charge so compressed by said plunger passes through the flutes 4' into the combustion chamber A', thereby completing the scavenging of the latter.

The valve 27' now closes and the power piston continues its downward stroke further compressing the charge and driving the same with great force through the flutes 4' into the combustion chamber A' thereby shooting the charge against the cylinder-head in a plurality of relatively small streams.

The compressed charge is now exploded and both pistons driven upwardly, the valve 27 opening prior to the explosion. Both pistons rise at the same rate of speed until the upper head 5 of the sub-piston nearly reaches the top of the cylinder, scavenging the combustion chamber A through the exhaust passage 26. The sub-piston is then recalled until the lower face of the upper head 5 is slightly above the inner ends of the flutes 4 and the upper face of its lower head 5' is slightly below the fuel inlet 42 whereupon it remains stationary until driven downwardly by the next explosion in the combustion chamber A.

The power piston continuing its ascent draws a charge of fuel from the inlet 42 into the trailing end of the hollow piston, *i. e.*, the space between its own lower face and the upper face of the lower head 5', and compresses the charge in the advancing end of said hollow piston, *i. e.*, the space between its own upper face and the lower face of the upper head 5. The scavenging of the combustion chamber A is completed by a portion of the compressed charge passing thereto by way of the flutes 4, whereupon the valve 27 is closed and the continued upward stroke of the power-piston drives the rest of the fuel charge through said flutes into

said combustion chamber and completes the compression thereof.

Ignition then occurs again and the cycle is repeated, there being one explosion at each end of every stroke or two per revolution of the crank-shaft.

In the foregoing description of the cycle no reference has been made to the outwardly-opening check valves 31, 31', which are removably held on their respective seats by the relatively light springs 32, 32', but it will readily be understood by inspection of Fig. 1, that every time one of the exhaust valves 27, 27' is opened mechanically, the pressure of the exhaust gas will open the co-operating check-valve.

When one of the heads of the hollow piston uncovers the flutes in either end of the cylinder, the space between such head of said hollow piston and the power piston *i. e.*, the advancing end of the hollow piston is brought into communication with the combustion chamber by way of said flutes before the power-piston begins to compress the charge in said space, and therefore, inasmuch as there is usually a partial vacuum in said space unless the engine is running at full load, it is desirable to provide automatic check-valves such as shown at 31, 31', or check-valves of any other suitable construction, to prevent any portion of the exhaust or the outside air from being drawn through the combustion chamber into this space by way of the flutes. I have found that such automatic check-valves greatly increase the efficiency of the engine.

During the upstroke of the cross-head 12, the plunger 47 of the oil pump will cause a quantity of oil to be forced through the tube 51 into the chamber 52 and thence by way of the tube 53 and duct 43 to the transverse ducts 44 in the power-piston head, thereby spreading on the interior wall of the cylinder 3 a coating of oil that has not been injured by the fire of the exploding charge, and at the same time the rods 6 are thoroughly lubricated to facilitate their passage through the power-piston. At every down-stroke of the power-piston the bracket 45 carries the lubricating pump downwardly and the spring 49 by retracting the plunger 47 from the lower end of the pump barrel causes a fresh charge of oil to be drawn from the source connected to the pipe 57 through the telescopic pipes 55, 56 and thence into the pump barrel.

This application is a division of my application Serial No. 19,265, filed April 5, 1915.

Having thus described an illustrative em-

bodiment of my invention without, however, limiting myself thereto, what I claim and desire to secure by Letters Patent—

1. In an internal combustion engine, a cylinder, a piston arranged to reciprocate therein and provided with an interior transverse duct extending to its periphery, a piston-rod connected to said piston and provided with a longitudinal duct communicating with the transverse duct in said piston, a cross-head connected to said piston rod, an oil pump carried by said cross-head for forcing a lubricating fluid through said ducts, a tube carried by said cross-head and communicating with said oil pump, a stationary tube fixed to the engine frame and having telescopic connection with the first mentioned tube, and a connection from said stationary tube to a source of oil supply.

2. In an internal combustion engine, a cylinder, a sub-piston within said cylinder, means for controlling said sub-piston, a plunger within said sub-piston, said plunger being provided with an interior transverse duct extending to its periphery, a piston-rod connected to said plunger and provided with a longitudinal duct communicating with the transverse duct in said plunger, rods secured to said sub-piston and connected to the sub-piston control means, said rods passing through bores in said plunger and said bores intersecting said transverse duct, and means for forcing a lubricating fluid through said ducts.

3. In an internal combustion engine, a cylinder, a power piston and a sub-piston arranged to reciprocate within said cylinder, said sub-piston being located between said power piston and the combustion chamber, means for controlling said sub-piston, said power piston being provided with an interior transverse duct extending to its periphery, a piston rod connected to said power piston and provided with a longitudinal duct communicating with the transverse duct in said power piston, rods secured to said sub-piston and connected to the sub-piston control means, said rods passing through bores in said power piston and said bores intersecting said transverse duct, and means for forcing a lubricating fluid through said ducts.

In testimony whereof, I have hereunto subscribed my name this 16th day of March, 1916.

FRED HENRY GILE.
